UNITED STATES PATENT OFFICE.

MAX W. JUDENFREIND, OF NEW YORK, N. Y.

DESIGN FOR A MUFF.

SPECIFICATION forming part of Design No. 29,775, dated December 6, 1898.

Application filed October 8, 1898. Serial No. 693,043. Term of patent 7 years.

To all whom it may concern:

Be it known that I, MAX W. JUDENFREIND, of the city of New York, borough of Manhattan, in the county and State of New York, have invented and produced a new and original Design for a Muff, of which the following is a full, clear, and exact description.

The design in its entirety consists of a muff-body B, on the front face of which and at the middle, near the top thereof, appears a raised rectangular frame A, on which is superimposed the cover or lid C, with a bow appearing under the lower portion of the frame and cover and extending with its ends downward and outward over part of the front of the muff-hairs, which latter appear radiating in

all directions from the said frame A and cover C as a center.

The leading feature of the design consists of a muff-body, on which appears raised a 20 rectangular frame with a superimposed cover or lid and with the muff-hairs appearing radiating in all directions from the said frame and cover as a center.

I claim—

The design for a muff, as herein shown and described.
